INVENTOR,
John S. Eddy,
By Mack & Sitzberg
attorney.

UNITED STATES PATENT OFFICE.

JOHN S. EDDY, OF LOS ANGELES, CALIFORNIA.

MEANS FOR HOLDING COVERS ON BEDS AND THE LIKE.

1,297,551.

Specification of Letters Patent. Patented Mar. 18, 1919.

Application filed August 5, 1918. Serial No. 249,560.

To all whom it may concern:

Be it known that I, JOHN S. EDDY, a citizen of the United States, and a resident of Los Angeles, in the county of Los Angeles 5 and State of California, have invented new and useful Improvements in Means for Holding Covers on Beds and the like, of which the following is a specification.

My invention relates to and has for a primary object the provision of means preferably attachable to the mattress whereby the ends of the bed covers at the foot of the bed may be firmly held in position thereon, the arrangement being such that the comfort of 15 the occupant of the bed will be greater than otherwise and in no wise impaired by the use of the attaching means.

A further object is to provide means extending across the entire width of the mattress at the end whereby the ends of the covers may be firmly clamped thereagainst and between the rolls of the mattress which are usually provided at the top and bottom edges, together with means attached to the 25 sides of the mattress whereby the means on the ends of the mattress may be removably attached thereto. Other objects will appear as the description progresses.

Referring to the drawing of my invention, 30 in which similar characters of reference are employed for indicating the same and like parts throughout the several views,

Figure 1 is a perspective view of a bed and mattress showing the use of my cover holding means thereon.

Fig. 2 is a fragmentary section of the end of the mattress and covers showing the main attaching member.

Fig. 3 is a side view of the means carried 40 by the mattress for connection with the main attaching member, whereby the latter may be held in position.

Fig. 4 is a perspective view of the said main attaching member.

As clearly shown in the drawings, especially in Fig. 1, my device comprises a main attaching or holding member 10 having the form of a bar and a length of about the same as the width of the mattress 11, and a 45 strap, as at 12, adapted to be suitably sewed or otherwise attached to the side edges of the mattress, hooks of wire or the like, as at 13, being attached as shown to the straps 12, over which cords 14 are stretched. The ends 50 14^a of the cords 14 are extended through perforations 15 in the ends of the main member

10 and tied with but a single knot, preferably, so that the loops of the cords may be hooked over the loops 16 of the hooks 13.

It will be observed that the under coverings 17, 18 and 19 are held firmly against the end of the mattress by means of the main bar member 10, this bar being preferably positioned between the rolled edges 11^a and 11^b of the mattress and the under coverings are 60 forced into firm contact with the mattress thereby and will ordinarily be held against accidental removal. The outer covering, or counterpane 20, extends downwardly over the sides and foot of the bed as usual and 65 covers the member 1, so that this member need not be of ornamental character.

In use, the under coverings are first pulled down over the foot of the mattress, the bar 70 10 is then positioned thereagainst, the cords 75 14 looped over the hooks 13 and the ends of the cords then tied so that a proper tension may be placed on the cords to insure against the untying of the cords and the removal or loosening of the holding bar 10.

It will be apparent that my device may be modified substantially from the form shown and that the manner of attachment to the mattress may be altered within the scope of the appended claims without enlarging the 85 scope or departing from the spirit of my invention.

Having thus described my invention, what I claim is:

1. In a bed clothes holder, the combination with a mattress, of attaching members secured to the opposite edges of said mattress near one end, a rigid bar extending across the end of said mattress and adapted to lie between the upper and lower edges 90 thereof, and means on the ends of said bar and adapted to be secured to said attaching members, for frictionally holding said bar in position on the mattress.

2. In a bed clothes holder, the combination with a mattress and bed clothes thereon, of a bar positioned at the end and between the upper and lower surfaces of said mattress, and coöperating attaching members carried on the ends of said bar and the sides of said 95 mattress, whereby said bar may be frictionally held on said mattress, said bar serving to hold the clothes firmly against the end of said mattress.

3. In a bed clothes holder, the combination with a mattress and bed clothes thereon, of straps attached to the edges of said mattress

near one end, a bar extending across the end of said mattress between the upper and lower sides thereof, the ends of the bed clothes being extended between the end of said mattress and said bar, and means on the ends of said bar for removably holding said bar in contact with said bed clothes, said means being attachable to said straps.

4. A bed clothes holder comprising, in combination with a mattress and bedding thereon, attaching members secured to the opposite edges of said mattress and at one

end thereof, a bar extending across the end edge of said mattress and adapted to hold said bedding thereagainst, and means on the ends of said bar adapted to be removably attached to said attaching members for holding said bedding irremovably against the end of said mattress. 15

JOHN S. EDDY.
